UNITED STATES PATENT OFFICE

158,471

ASH TRAY

Ruby Ruth Krepela, Inglewood, Calif.

Application December 3, 1948, Serial No. 149,934

Term of patent 14 years

(Cl. D85—2)

To all whom it may concern:

Be it known that I, Ruby Ruth Krepela, a citizen of the United States, residing at Inglewood, in the county of Los Angeles and State of California, have invented a new, original, and ornamental Design for an Ash Tray, of which the following is a specification, reference being had to the accompanying drawing, forming part thereof.

Fig. 1 is a perspective view of an ash tray, showing my new design.

Fig. 2 is a top plan view; and

Fig. 3 is a side elevational view.

I claim:

The ornamental design for an ash tray, as shown.

RUBY RUTH KREPELA.
